US0D1058235S

(12) United States Design Patent (10) Patent No.: US D1,058,235 S
(45) Date of Patent: * Jan. 21, 2025

(54) INFLATABLE PILLOW

(71) Applicant: Yanwu Li, Yueyang (CN)

(72) Inventor: Yanwu Li, Yueyang (CN)

() Term: 15 Years

(21) Appl. No.: 29/911,896

(22) Filed: Sep. 11, 2023

(51) LOC (15) Cl. 06-09

(52) U.S. Cl.

USPC D6/604; D6/601

(58) Field of Classification Search

(57) CLAIM

The ornamental design for an inflatable pillow as shown and described.

DESCRIPTION

FIG. 1 is a perspective view of an inflatable pillow showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is bottom plan view thereof.

1 Claim, 8 Drawing Sheets
